UNITED STATES PATENT OFFICE

LEO EDELMANN, OF CHICAGO, ILLINOIS, ASSIGNOR TO E. EDELMANN & CO., OF CHICAGO, ILLINOIS, A CORPORATION OF ILLINOIS

HYDROMETER

Application filed August 6, 1926. Serial No. 127,662.

My present invention relates to hydrometers, and particularly to a hydrometer of the syringe type and a float element therefore.

5 An object of this invention is to provide a structure with which the float element is held out of contact with the liquid tube or barrel and is cushioned therefrom.

Another object resides in so constructing 10 the parts that the float element is supported in a manner to permit free ingress and egress of the liquid.

Still another object lies in so constructing 15 the parts that my invention is adaptable to hydrometer and float structures of various constructions and forms.

With the above and other objects in view, which will be apparent to those skilled in the art, this invention includes certain novel 20 features of construction and combination of parts which will be pointed out in connection with the drawing.

In the drawing:

Figure 1 is a vertical sectional view 25 through one type of hydrometer showing my invention embodied therewith.

Fig. 2 is a view in perspective of one of the float positioning and cushioning rings.

Fig. 3 is a perspective view showing the 30 float spacing and cushioning cap.

Fig. 4 is a view in elevation of a float illustrating a modified adaptation.

Figs. 5, 6 and 7 are fragmentary sectional 35 views to illustrate different forms which the cushioning band might take.

Figs. 8 and 9 are fragmentary sectional views showing modified adaptations of the cap.

The hydrometer, as illustrated in Fig. 1, 40 has the usual barrel 1 provided with a suction bulb 2 at one end and a liquid spout 3 at the remaining end. This liquid spout has the passage 4 thereof opening into the barrel or tube 1 through a flat end 5.

45 The float 6, which is of any desired form and construction, is placed within the tube or barrel 1, and as it is customary to make the float element 6 and the barrel 1 of glass or other transparent frangible material, these parts are readily broken through

shocks transmitted from the one to the other when the hydrometer is in use or when it is accidentally dropped or otherwise jarred. Further, the float element is likely to adhere to the barrel, by capillary attraction, and thus increase the frictional contact to such an extent as to prevent or interfere with accurate readings. To avoid these objections I provide a ring 7 around the upper extremity of the float chamber 8 which ring is of rubber or other cushion material not readily affected by acids or other liquids likely to be tested by the use of the hydrometer. This band 7 is preferably of more or less elastic rubber so that it will fit 55 and hold in place upon the float chamber, and radially extending lugs or projections 9 are provided on the band to extend therefrom, preferably at three or more points spaced around the circumference of the 60 band. These projections 9 are so formed that the float element 6 can move freely within the barrel 1, but that the gauge stem 10 thereof will be at all times spaced from the wall of the tube or barrel 1. 65

A cap 11, of rubber or other cushion material, is provided to be fitted over the lower end of the float chamber 8, and has radially extended projections or lugs 12 to hold the float element spaced from the inner wall 70 of the barrel and to reduce frictional contact. This cap 11 has one or more foot lugs or projections 13 which project from the end of the cap to hold the hydrometer element spaced from the plain end of the 75 spout 3 so that liquid can flow freely through the inner end of the passage 4. As shown in Fig. 3, it is perhaps preferable that the cap 11 be slightly reduced at its open end so that it will be stretched over 80 and will consequently hold in place upon the end of the float chamber 8. 85

In Fig. 4 I have shown the cap 14 without the end legs or projections, and this cap is fitted upon the weight bulb of the hydrometer, the hydrometer element 15 in this instance being of the type having the weight chamber or bulb distinct from the float chamber. Also, I have shown the ring 16 90 of smaller diameter than ring 7 so that it 95

will fit and hold upon the upper end of the gauge stem 17. In this adaptation the lugs or projections 18 are made longer to project sufficiently to hold the float chamber 15 from contact with the inner wall of the barrel 1.

5 While I have illustrated the band 7 as being flat as better shown in Fig. 5, this band might be grooved on its inner side as shown at 7^a in Fig. 6, to fit over a circumferential rib 8^a on the float chamber. Further, the band might be provided with an inner peripheral rib 7^b, as shown in Fig. 7, to fit into a circumferential groove 8^b on the float chamber.

10 In Fig. 8 I have shown the cap 19 provided with an end opening 20 so that air will not be caught and pocketed within the cap when this is fitted in place upon the end of the float chamber; however, in some instances it may be found desirable to provide an air cushion at this end, one convenient manner of accomplishing this being illustrated in Fig. 9, where the cap 21 is recessed as at 22 to provide an air pocket and cushion on the lower end when the cap is fitted upon a float element. The caps 11 and 14 may be formed with similar recesses.

15 The specific gravity of rubber or other cushion material used in the formation of the cushion bands or caps can be taken into account when the float element is being calibrated, and in this way the float can be accurately gauged. Also, it is possible to 20 more accurately form the float element and balance the same where the float chamber is made relatively plain than where it is necessary to apply beads or points to hold the float spaced from the barrel. Where the 25 air cushion is provided, as at 22, this must be taken into account in calibrating the float.

30 With a hydrometer constructed in accordance with my invention it will be possible to use two of the bands 7 upon the float element and dispense with the cap 11. In some instances a single band may be found sufficient, and other adaptations may function to better advantage with a single band 35 7 around the float chamber and a band 16 around the gauge stem. The main purpose of my invention is to provide a structure with which the float element is spaced from the tube or barrel by cushion means, and the 40 cushion means is constructed to reduce frictional contact and give a maximum cushioning effect. As the lugs or projections upon the bands and caps are relatively small and will be in most instances more or less tapered 45 or pointed to reduce frictional contact, a highly efficient cushion between the float element and the barrel is obtained.

50 While I have herein shown and described only certain specific embodiments of my invention and have suggested only certain pos-

sible modifications, it will be appreciated that changes and variations can be resorted to without departing from the spirit and scope of my invention.

I claim:

1. A hydrometer including a float element having a member of cushioning material fitted thereon and provided with projecting lugs, also of cushioning material and of substantially conical bead-like form. 70

2. A hydrometer comprising a barrel, a float element movable in said barrel, and a member of cushioning material carried by the float element and provided with projections also of cushioning material and of substantially conical bead-like form to space the element from the barrel. 75

3. A hydrometer comprising a float barrel, a float element movable within the barrel, and a band of cushioning material fitted around the float element and provided with projections also of cushioning material and of substantially conical bead-like form to space said element from the barrel. 80

4. A hydrometer comprising a float containing member, a float movable within said member, and a band of cushion material fitted upon the float element and provided with radially extending projections of substantially conical bead-like form and also of cushion material. 85

5. A hydrometer comprising a float barrel, a float element within the barrel, a cap of cushion material carried at one end of the float element, and a band of cushion material carried by the float element and spaced from the cap. 90

6. A hydrometer comprising a float barrel, a float element within the barrel, a cap of cushion material carried at one end of the float element, and a band of cushion material carried by the float element and spaced from the cap, said cap and band being provided with radially extending projections. 95

7. A hydrometer comprising a float barrel, a float within the barrel, and a cap of cushion material mounted on the lower end of the float element and provided with radial projections to space the float element from the barrel. 100

8. A hydrometer comprising a float barrel, a float within the barrel, and a cap of cushion material mounted on the lower end of the float element and provided with radial projections to space the float element from the barrel, said cap having a recess at its end to give added cushioning effect at this point. 105

9. The combination with a hydrometer float element of a cap fitted on the lower end of the float element and provided with radially extending lugs and having projecting foot lugs at its end. 115

10. The combination with a hydrometer float element of a cap fitted on the lower end 120

of the float element and provided with radially extending lugs and having projecting foot lugs at its end, and a band of cushion material fitted upon upon the float element 5 at a point spaced from the cap and provided with radially projecting lugs.

11. The combination with a hydrometer float element of a cap of cushion material fitted upon the lower end of the float element 10 to cover the bottom and side portions thereof, said cap being provided with end projecting lugs also of cushioning material and of substantially conical bead-like form.

12. The combination with a hydrometer 15 float element of a cap of cushion material fitted upon the lower end of the float element to cover the bottom and side portions thereof, said cap having laterally projecting lugs of cushioning material and of substantially 20 conical bead-like form extending from the side wall thereof.

13. The combination with a hydrometer float element of a cap of cushion material fitted upon the lower end of the float element 25 to cover the bottom and side portions thereof, said cap having radial and end projecting lugs on the side and end thereof to space the float element centrally within a float barrel and to hold the float against 30 closing a spout opening within a hydrometer.

In testimony whereof I hereunto affix my signature.

LEO EDELMANN.
